Patented Dec. 22, 1914.

UNITED STATES PATENT OFFICE.

EMMA J. WHITMAN, OF OAKLAND, CALIFORNIA.

THEATER-SEAT HAT-HOLDER.

1,121,959.

Specification of Letters Patent. Patented Dec. 22, 1914.

Application filed March 24, 1914. Serial No. 826,899.

To all whom it may concern:

Be it known that I, Mrs. EMMA J. WHITMAN, a citizen of the United States residing at Oakland, in the county of Alameda and State of California, have invented new and useful Improvements in Theater-Seat Hat-Holders, of which the following is a specification.

This invention relates to improvements in hangers, for hats, garments and other articles, and is especially constructed for application to the backs of seats, in theaters or other places of assembly where ordinances require the removal of hats, and 15 there is a consequent need of a proper support therefor, and for other articles of dress.

The object of the invention is to provide a simple, substantial, cheaply manufactured hanger or hook, which is so constructed that 20 it may be swung to one side or the other of the back of the seat to which it is attached when not in active use, and is so shaped that it will not obstruct or hinder persons desiring to pass between the seats, nor present 25 any sharp or angular projecting parts liable to catch in the wearing apparel of the person passing.

Another object of the invention is to provide the hanger with a spring-actuated cam 30 which will hold the hanger either in the closed or extended position.

Figure 1 is a side elevation partly in section, of the back of a chair, showing the application of the invention. Fig. 2 is a perspective of the hat hanger with supporting bracket. Fig. 3 is a plan view of the back of a chair showing the application of the device. Fig. 4 is an enlarged section on line X—X, Fig. 2, showing the position of the cam when 35 the hanger is extended. Fig. 5 is a similar section, showing the position of the cam when the hanger is folded to one side.

Referring to the drawings, A indicates a bracket plate which is adapted to be secured 40 to the back of a seat as at B, in any suitable manner, or as here shown, by screws 2. Secured to the plate, or formed integrally with same is a pair of projecting bearing flanges 3 and 4 in which is pivotally mounted a rod 45 5. The lower end of the rod is reduced in diameter as at 6, to form a shoulder which will prevent the rod from slipping down through the bracket bearings 3 and 4, while the upper end of the rod is considerably extended and slightly bent as at 7 to form a hook or hanger upon which hats or other ar-

ticles of wearing apparel may be disposed. Suitably secured to the rod as at 8 is a cam member 9, and secured to the bracket as at 10 is a spring member 11, which is so positioned as to engage with the inner surface of the cam and exert its pressure thereon. The inner face of the cam which engages with the spring when the hanger is swung out into the extended position, indicated in Figs. 1, 2 and 3, is flat as indicated at 12, and considerably wider than any other portion of the cam, the large bearing surface thus produced upon which the spring pressure is exerted is more than sufficient to hold the hanger in the extended position. The sides of the cam are similarly flattened, as indicated at 13 and 14, to provide surfaces with which the spring may engage to hold the hanger in the closed position.

The hanger here shown is simple and substantial in construction, and cannot possibly get out of order. The pivotal mounting of the hanger permits it to be swung to either one side or another against the back of the seat, as indicated by dotted lines at 15 and 16, in Fig. 3 where the space consumed is the smallest possible, and where it cannot interfere with a person passing.

The angular form of the hanger gives a 45 very large opening or capacity when in the extended position, thus permitting hats of large size to be accommodated without subjecting them to any unnecessary pressure which might destroy the shape or crush the 50 trimmings.

The upper end of the hanger is preferably provided with a knob 18 constructed of resilient material, such as rubber or the like. The knob thus applied does not only act as 55 a head for the hanger, but also serves the function of a cushioning member which prevents the hanger from coming into actual contact with the surface of the seat, thus deadening the sound of contact when the hanger is swung into closed position and also preventing the surface from becoming marred.

Another important advantage gained by the peculiar construction of the hanger is 60 this: A person leaving his or her seat, and forgetting to close the hanger, does not inconvenience another person desiring to pass, for the simple reason that the hanger swings closed by itself in either direction by the 65 slight pressure which is exerted upon it when contacting with the passing person.

The materials and finish of the several parts of the device are such as the experience and judgment of the manufacturer may dictate.

5 I wish it understood that various changes in form, proportions and minor details of construction may be resorted to within the scope of the appended claim, and that I do not wish to limit myself to the specific de-
10 sign and construction here shown.

Having thus described my invention, what I claim and desire to secure by Letters Patent is:

15 The combination with a seat back of a plate adapted to be secured thereto, upper and lower flanges disposed at right angles to the plate, a leaf spring having its lower end fixed to the lower end of the plate, the upper end of said spring being spaced from the
20 plate and disposed adjacent the upper flange, a rod journaled in the upper flange and hav-

ing a bearing in the lower flange, a cam de-
tachably connected to the rod and bearing against the under surface of the upper flange to prevent upward movement of the rod, 25
said cam having a flat front face and con-
vergingly arranged side faces, the upper end
of said rod terminating in an angularly dis-
posed hanger, the upper end of the hanger
being adapted to yieldably engage the seat 30
back when either one of the side faces of the
cam is engaged with the spring, and to be
held spaced from said back when the spring
engages the front face of the cam, as and for
the purpose set forth. 35

In testimony whereof I have hereunto set
my hand in the presence of two subscribing
witnesses.

Mrs. EMMA J. WHITMAN.

Witnesses:

LILLIAN M. WISEHART,
MURIEL ZAHN.
